SEAL FOR ROTATABLE CLOSURE PLATE ON
TRANSIT TYPE CONCRETE MIXERSArmand J. Pasquariello, Newark, N. J., assignor to
Worthington Pump and Machinery Corporation,
Harrison, N. J., a corporation of Delaware

Application November 14, 1949, Serial No. 127,110

1. Claim. (Cl. 259—161)

1 This invention relates generally to concrete mixing apparatus of the transit type such as truck mixers and more particularly to a sealing structure between the rotating and non-rotating portions of the closure means provided thereon.

It will be understood that while this invention is described in connection with transit type concrete mixers, that it is applicable to any type of concrete mixer wherein the closure means has a rotatable and a non-rotatable portion.

Truck mixers, as the transit type concrete mixers are conventionally called, are utilized principally for rapidly transporting concrete or the ingredients therefor some distance away from the initial mixing point. They usually comprise a mixing drum rotatably mounted on a truck chassis with suitable means adapted for rotating the mixer, and elevated axial opening at the rear end of the mixer being used both for loading and for discharging the mixing drum, special blading within the drum effecting the mixing when the drum is rotated in one direction and ejection of the material when the drum is rotated in the opposite direction.

In the prior art, one type of closure means for the axial opening comprises a combined charging hopper and closure wherein the closure is usually a plate-like member which cooperates with a seat around the axial opening in the drum. It is preferred to have the charging hopper so arranged that it may be swung away from the mixing drum for the purpose of discharging the drum, and accordingly it is usually mounted on suitable framing and is not rotatable with the mixing drum. Thus, the closure plate may be either fixedly connected to the charging hopper or it may be rotatably connected to the charging hopper, seating itself in any suitable manner. In the latter case it will rotate with the mixing drum when it is in operation.

It is with this latter type of closure plate that the present invention deals. With this type of rotatable closure plate a movable surface is created between the rotatable closure plate and the non-rotatable charging hopper which must be provided with a suitable seal to prevent leakage from the mixing drum and wear between the rotating surfaces.

Accordingly, it is an object of the present invention to provide a seal between the rotatable

2

closure plate and the non-rotatable charging hopper on a transit concrete mixer.

It is another object of the present invention to provide a seal which is easily accessible and may be easily changed when it needs replacement.

It is a further object of the present invention to provide a seal which will be kept free of dirt and other foreign matter and which can be easily lubricated to provide a substantially frictionless surface.

With this and other objects in view as may appear from the accompanying specification, the invention consists of various features of construction and combination of parts which will be first described in connection with the accompanying drawings showing a seal for charging hopper and rotatable closure plate on transit type concrete mixers of a preferred form embodying the invention, and the features forming the invention will be specifically pointed out in the claim.

In the drawings—

Figure 1 is a side elevation of the discharge end of a transit type concrete mixer showing the invention in section thereon.

Figure 2 is an enlarged vertical section of the invention.

Referring to the drawings, Figure 1 shows a fragment of the mixing drum 1 and a frame 2 which are mounted on a main frame bolted to a truck chassis (not shown). Mounted to the frame 2, to oscillate to and away from an axial opening 3 at the end of the mixing drum 1, is a combined charging hopper and closure 4. The charging hopper and closure 4 is to provide easy means for both loading the mixing drum and closing the axial opening thereon during the mixing or transit of materials forming the concrete.

Axial opening 3 has an annular flange 5 formed thereon. Attached thereto by suitable means is a second annular flange 6 formed on an annular member 7. The outer portion of the member 7 away from the mixing drum 1 is provided with an annular tapered lip 8 which is engaged in valve-like seating arrangement by a dished closure plate 9, all of which is clearly shown in Figure 1 of the drawings.

The closure plate 9 is connected to the discharge end of a funnel-shaped feed hopper 10 by a rotatable surface bearing and support member 11 hereinafter described. The funnel-shaped

feed hopper 10 will be constructed to provide unrestricted passage therethrough, an opening 12 of substantially the same diameter as the discharge end of the feed hopper 10 being provided on the dished closure plate so that ingredients placed in the hopper will pass into the mixing drum 1. The rotatable bearing and support member 11 provides means for allowing the closure plate to rotate with the mixing drum when it is in operation as the weight of the charging hopper and closure will hold the convex surface 13 of the closure plate 9 in contact with the tapered lip 8 as is shown in Figure 1 of the drawings.

Rotatable surface bearing and support member

The rotatable surface bearing and support member 11 comprises an annular outer seal ring 14 which is engaged by an annular inner seal ring 15 as hereinafter described. The outer seal ring 14 is fixedly connected to the discharge end of the feed hopper 10 by suitable means such as bolts 16 and nuts 17, and the inner seal ring 15 which engages the outer seal ring 14 is in turn connected to the dished closure plate 9 by suitable means such as bolts 18 and nuts 19, all of which is clearly shown in Figure 2 of the drawings.

Outer seal ring 14 forms one surface of the rotatable surface bearing and support member 11. It has a substantially flat annular rim shape being connected on the inner end thereof to the discharge end of the feeding hopper as above stated. In the medial portion of the rim a side member 20 extends inwardly towards the axial opening 3 of the mixing drum at a substantially right angle to the rim portion of the seal ring 14. An annular groove 21 and a shoulder 22 are formed on the outer surface of the side arm 20 whereby an inner annular projection 23 is formed on the axial opening side of the annular groove 21 and an outer annular projection 24 is formed on the side of the annular groove 21 closest to the discharge end of the feed hopper as is clearly shown in Figure 2 of the drawings.

The inner seal ring 15 forms the other surface of member 11 and is also a substantially flat rim-like member which has a flange 25 constructed and shaped to snugly engage the annular groove 21 and those portions of the inner and outer annular projections 23 and 24 adjacent thereto. An annular insert 26 is formed in the inner seal ring 15 and forms substantially a continuation of the shoulder 22 on the outer seal ring 14. This insert 26 will provide means for fixedly connecting the sealing means 27 to the dished closure plate 9.

Inner seal ring 15 and the outer seal ring 14 as above described, form the rotatable surface-to-surface bearing for the closure member 9 and act to support member 9 so that it will be movable with the feeding hopper 10 thus forming the combined charging hopper and closure 4 above mentioned.

Sealing means

The sealing means 27 is a flat annular member preferably of a resilient material although any similar type gasket material of which there are many well known types on the market may be utilized for this purpose. A portion thereof is firmly held in the insert 26 between the inner seal ring 15 and the dished closure plate 9 whereby it will be rotatable therewith. The dished closure plate 9 extends up past the sealing means 27 on the axial opening side thereof, acting to enclose

the sealing means 27 and to reduce the amount of contacting area with the ingredients passing through the charging hopper and closure 4.

Thus when the inner seal ring 15 is in engagement with the outer seal ring 14, the portion of the sealing ring which is not held by the insert will extend up and engage the shoulder 22 on the outer seal ring 14 in surface-to-surface relationship and in this position will lie adjacent the rotatable surface bearing and support member 11. That portion of the closure plate 9 which extends past the sealing means abuts the end of the side member 20 leaving a line-like opening 28 as the only opening through which the ingredients passing through charging hopper and closure 4 may contact the sealing means 27 thus aiding the sealing means to prevent grit or foreign matter from passing to the adjacent bearing and support structure 11, as is clearly shown in Figure 2 of the drawings.

Since the above described members forming the rotatable surface bearing and support member 11, and the sealing means are in surface-to-surface engagement, lubrication means is provided therefor. A passage 29 being provided in the side member 20 extending to the outer side thereof. An Alemite lubrication fitting 30 threadably engages the outer end of this passage whereby lubricant may be forced into the passage 29 by any suitable means. The other end of the passage 29 communicates with a transverse passage 31 formed in the inner projection 23 and opening at the point where surface-to-surface contact is made between the outer and inner seal rings 14 and 15 whereby lubricant will pass along these surfaces and diffuse outwardly therefrom to the other portions in surface-to-surface engagement such as the sealing means 27 and the shoulder 22.

In operation, the charging hopper and closure 4 is manually moved by handle 32 towards the axial opening 3 until the convex surface 13 of the closure plate 9 comes into snug contact with the tapered lip 8. The mixing drum 1 is then loaded and the concrete mixed by rotation of the drum. As the drum rotates, the closure plate will rotate therewith in the rotatable surface bearing and support structure 11 above described. The line-like opening 28 allows only a minimum contact between the ingredients and the sealing means 27 and the sealing means prevents any grit or other foreign matter from passing down the shoulder 22 which it engages during rotation into the rotatable surface bearing and support member 11.

When it is desired to change the sealing means, all the operator need do is oscillate the charging hopper or closure 4 outwardly till it clears the axial opening and then loosen bolts 19 and remove the dished closure plate 9. The sealing means 27 is now easily removable and may then be replaced by a new member.

It will be understood that the invention is not to be limited to the specific construction or arrangement of parts shown, but that they may be widely modified within the invention defined by the claim.

What is claimed is:

In a combined charging hopper and closure for the axial opening of the mixing drum on a transit type concrete mixer, a feeding hopper having an open unrestricted discharge, an outer seal ring fixedly connected to said feeding hopper, an annular groove formed in said outer seal, a rotatable closure plate adapted to sealingly engage said axial opening of the mixing drum and to revolve

therewith, an inner seal ring fixedly connected to said closure plate and having a flanged portion for engagement with said annular groove whereby a surface bearing and support structure is provided for the closure plate to rotate in, sealing means fixedly mounted on said closure plate between the closure plate and the inner seal ring and to rotate therewith, said sealing means adjacent said surface bearing to prevent grit and foreign matter from entering therein, and means 10 for lubricating the said bearing and sealing means to provide substantially frictionless rotation.
